(57) **CLAIM**

I claim the ornamental design for a therapeutic device, as shown and described.

DESCRIPTION

FIG. 1 is a perspective view of the claimed design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is an exploded perspective view thereof; and,

FIG. 9 is a perspective view showing the claimed design on the arm of a person.

The broken lines in the figures are for the purpose of depicting environment and form no part of the claim.
